Primary Examiner — Lakiya G Rogers*Assistant Examiner* — Elisabeth M Lange(74) *Attorney, Agent, or Firm* — McAndrews, Held & Malloy, Ltd.(57) **CLAIM**

The ornamental design for a table with attached seat, as shown and described.

DESCRIPTION

FIG. 1 is a top and front, right side perspective view of a table with attached seat showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the drawings illustrate portions of the table with attached seat that form no part of the claimed design.
